FIG. 1.

FIG. 2.

FIG. 3.

David H. Elkins, ^{Inventor}

By J. E. Stabbins, ^{Attorney}

UNITED STATES PATENT OFFICE.

DAVID HENRY ELKINS, OF AMESBURY, MASSACHUSETTS, ASSIGNOR TO GRAY & DAVIS, INC., OF BOSTON, MASSACHUSETTS, A CORPORATION OF MASSACHUSETTS.

DESIGN FOR AN AUTOMOBILE-LAMP.

47,915.

Specification for Design.

Patented Oct. 5, 1915.

Application filed May 3, 1915. Serial No. 25,616. Term of patent 7 years.

To all whom it may concern:

Be it known that I, DAVID HENRY ELKINS, a citizen of the United States, residing at Amesbury, in the county of Essex, State of Massachusetts, have invented a new, original, and ornamental Design for Automobile-Lamps, of which the following is a specification, reference being had to the accompanying drawing, forming part thereof.

Figure 1 is a front view in elevation of a

lamp showing my new design. Fig. 2 is a top plan view of Fig. 1. Fig. 3 is a side view in elevation.

I claim:

The ornamental design for an automobile lamp, substantially as shown.

DAVID HENRY ELKINS.

Witnesses:

M. PERRY SARGENT,

DANIEL C. MAXFIELD.
